UNITED STATES PATENT OFFICE.

HERBERT J. HOPE, OF SANFORD, MAINE.

PILE-FABRIC LOOM.

1,304,879.

Specification of Letters Patent. Patented May 27, 1919.

Application filed August 31, 1917. Serial No. 189,054.

To all whom it may concern:

Be it known that I, HERBERT J. HOPE, a citizen of the United States, residing at Sanford, county of York, State of Maine, have 5 invented an Improvement in Pile-Fabric Looms, of which the following description, in connection with the accompanying drawing, is a specification, like characters on the drawing representing like parts.

10 This invention relates to pile fabric looms of that type which are constructed for weaving figured goods, and the object of the invention is to provide a novel means for controlling the pile warps so that they can be 15 taken from a warp beam instead of from a creel of single spools.

In the weaving of a pile fabric to produce figured goods, it is customary to have the different-colored pile warp threads or the 20 different sets of warp threads from which the figures are made controlled by different harnesses, and as the different sets of pile warp threads which are controlled by different harnesses are called for at different 25 times, it is customary to use a creel of separate spools for the various pile warp threads, so that the proper tension may be maintained on each warp thread independently.

30 The object of my invention is to provide a novel tension-controlling device for the various sets of warp threads by which the tension of each set of threads that is controlled by each harness can be varied independently, thus permitting the threads to be 35 all taken from the same warp beam and yet to produce a satisfactory fabric.

In order to give an understanding of my 40 invention, I have illustrated in the drawings a selected embodiment thereof which will now be described, after which the novel features will be pointed out in the appended claims.

Figure 1 is a diagrammatic view showing 45 the harness frames of a pile fabric loom and also showing my improved tension device;

Fig. 2 illustrates somewhat diagrammatically the dobby mechanism or head motion for operating the harnesses.

50 Inasmuch as the invention relates to the tension-controlling means for the various sets of warp threads, I have not thought it necessary to illustrate a complete loom.

In Fig. 1 I have indicated a plurality of 55 harness frames, the two frames 1 and 2 being those which control the ground warp

threads 3 and 4, and the harness frames 5, 6, 7, and 8, being those which control the pile warp threads 9, 10, 11 and 12. It will be understood, of course, that each harness frame 5, 6, 7 and 8 will control a plurality of warp threads, the number depending upon the character of the pattern to be produced. In the weaving of the fabric, the harness frames 5, 6, 7 and 8 are operated by 60 suitable mechanism to bring up at each pick of the loom the desired sets of warp threads 9, 10, 11 and 12 according to the pattern to be produced, it being understood that in the weaving of the goods the pile wires will be 65 inserted as the shed is formed to produce the desired pile fabric. The pattern produced will, of course, depend upon the order in which the harness frames 5, 6, 7 and 8 are raised or lowered. These harness frames 70 may be operated by any suitable pattern mechanism, such as usually employed in fancy weaving. I have illustrated in Fig. 2 a well-known type of pattern mechanism known to the trade as the "Knowles head 75 motion" and which comprises a plurality of harness levers 13 pivoted at 14, there being one lever for each of the harness frames 5, 6, 7 and 8, each lever being connected to its harness frame by the flexible connections 80 15, 16. Each harness lever is connected by a connection 17 with a so-called vibrator gear 18, and the vibrator gears are adapted to be rotated in one direction or the other thereby to raise or lower the harness frames 90 by means of either one of two cylinder gears 19 and 20. Each vibrator gear 18 is carried by a lever 21 and the levers 21 are controlled by the usual pattern chain 22. As the pattern chain is moved forwardly, the levers 21 95 are raised or lowered according to the construction of the pattern chain thereby bringing the various vibrator gears into engagement with either the cylinder gear 20 or the cylinder gear 19.

Inasmuch as the above-described pattern mechanism is one that is familiar to those skilled in the art, I have not thought it necessary to enter into a more detailed description thereof.

100 In weaving a fancy pile fabric and especially one having a small figure in the pile warps, it is necessary to maintain a proper tension on the pile threads which are not looped over the pile wires to form the figure 110 of the fabric, and I provide for this by a novel construction which involves a plural-

100

110

ity of tension rods, one for each of the sets of warps 9, 10, 11, 12, each tension rod operating to place tension on the warps of one set only. By thus controlling the tension of each set of warp threads 9, 10, 11 and 12 separately, it is possible to take the warp threads from a warp beam 40 instead of from separate spools. In the illustrated embodiment of my invention, the tension rods 10 are indicated at 23, 24, 25 and 26, respectively, the tension rod 23 being applied to the set of warp threads 9; the tension rod 24 being applied to the set of warp threads 10; the tension rod 25 being applied to the set 15 of warp threads 11; and the tension rod 26 being applied to the set of warp threads 12. These tension rods have their ends guided in suitable guide members or boxes 27 which are supported on the loom frame 28. Each 20 box is shown as having a plurality of guiding grooves or slots 29 therein in which the ends of the tension rods are freely received. The member 27 is also shown as sustaining two supporting bars 30 and 31 over which 25 all the pile warp threads pass, said warps being taken from a suitable warp beam 40 and passing around the guiding bars 33. In practice, all the warp threads except those of the set 9 will pass over the tension 30 rod 23, the warp threads of the set 9 passing under said rod 23 so that said warp threads 9 support the weight of the rod 23. Similarly, all of the pile warp threads except the set 10 pass over the tension rod 24, the warp 35 threads 10 passing under said tension rod and supporting the weight thereof. Similarly, all the warp threads except the set 11 will pass over the tension rod 25, and all except the set 12 will pass over the tension 40 rod 26. Thus the weight of the tension rod 23 is supported by the warp threads 9 only; the weight of the tension rod 24 is supported by the warp threads 10 only; the weight of the tension rod 25 is supported by the warp 45 threads 11 only; and the weight of the tension rod 26 is supported by the warp threads 12 only.

The guiding slots 29 are of considerable length so as to allow for a considerable 50 range of movement of the tension rods. The

various tension rods may be of different sizes and weight, dependent on the amount of tension necessary to be applied to each set of pile warps. This will, of course, depend something upon the number of warps 55 in each set. During the weaving operation, each tension rod acts on its particular set of warp threads to maintain the required tension thereon so that if during the weaving any set of warp threads is not called for 60 for several picks the requisite tension may be maintained on said warp threads even though the warp threads which are brought up to produce the figure in the pile are being drawn from the warp beam faster than the 65 warp threads which are not so selected. By means of this invention it is possible to take the pile warp threads directly from warp beams instead of from single spools and yet to maintain the desired tension on the 70 threads of each set.

I claim:

1. In a pile fabric loom for weaving figured goods, the combination with a warp beam carrying a plurality of pile warp 75 threads which are divided into groups or sets, of a separate harness frame controlling each set of pile warp threads, means for actuating said harness frames selectively, and a separate tension rod for each set of pile 80 warp threads, said tension rods being independent from each other, and each tension rod being sustained entirely by the warp threads of the corresponding set.

2. In a pile fabric loom for weaving figured goods, the combination with a warp beam carrying a plurality of pile warp threads which are divided into groups or sets, of a separate harness frame controlling each set of pile warp threads, means for actuating said harness frames selectively, and a plurality of separate tension rods, one for each set of pile warp threads, each tension rod being supported entirely by the warp threads of the corresponding 95 set and having a weight proportionate to the number of warp threads in the set.

In testimony whereof, I have signed my name to this specification.

HERBERT J. HOPE.
